UNITED STATES PATENT OFFICE.

LYMAN RHOADES AND JOHN PHILIP SIPP, OF NEW YORK, N. Y.

KEY-HOLE GUARD.

SPECIFICATION forming part of Letters Patent No. 289,446, dated December 4, 1883.

Application filed August 1, 1883. (No model.)

To all whom it may concern:

Be it known that we, LYMAN RHOADES and JOHN PHILIP SIPP, citizens of the United States, residing in the city, county, and State of New York, have invented a new and useful Lock-Guard for Locks having attached to them H. R. Towne's key-hole guard, patented May 17, 1870, No. 103,256, and for the well-known lock known in the market as the "Isham lock," patented 1856-7, or "New Britain lock," and the lock first patented June 22, 1858, to Stuart Perry, and numbered 20,658.

Our invention relates to an improvement in lock-guards for locks having the invention of Towne attached to them, and for the Perry and Isham patent locks; and the objects of our improvement are to protect them so that they can not be locked or unlocked with their proper key, to do this without altering the lock in any way or even unlocking it, and with little expense.

Our invention is of great use to safe-deposit companies, when, for any reason it is desired to prevent a box-renter's box having one of said locks on it from being opened with its regular key except by a person properly authorized, and to prevent its being accidentally opened by an attendant causing the seal which may be attached to it to be broken. We attain these objects by our invention shown in the accompanying drawings, in which—

Figure 1 represents our invention and the manner of applying it to a lock having Towne's invention attached to it, and Fig. 2 represents our invention and the manner of applying it to the Perry lock and the Isham lock.

Similar letters refer to similar parts throughout the several views.

x represents what, for the sake of description, we shall call in both figures the "key-hole" of the lock to be guarded.

a represents a straight piece of metal with a handle, for the purposes hereinafter described.

45 *s* represents an eye-hole in the handle of *a*. *b* represents a piece of thin metal shaped to fit on the locks, as shown in the several views.

t represents an eye-hole in the raised part of *b*.

50 *c* represents any ordinary small padlock. In Fig. 1, *A* represents the key-hole of the lock to be guarded and Towne's invention at-

tached to it. *B* represents the same with our invention applied to it. *I* represents Towne's patent key-hole guard. *z* represents the shield or guard of Towne's invention intended to cover the key-hole. *b* in this view is shaped to fit on *z*.

In Fig. 2, *C* represents the Perry lock and Isham lock. *C'* represents a view of the face of the hub of a different form of the Perry lock and of the Isham lock. *D* represents the same as *C* with our invention applied to it. *D'* represents a side view of *C'* with our invention applied to it. *E* represents a side view of *C*, showing one of the two pins for fastening the register to the lock. *b* is shown as shaped and arranged to fit on the face of *C*; *b'* as shaped to fit on *C'*, and consists of a piece of thin metal bent at about a right angle, with eye-holes *y* and *t*, one in each face. In the drawings only the eye-hole *y* is shown. *l* represents the pins intended for the register of the lock *C*, and used to fasten *b* to its face. *m* and *n* represent slots for attaching *b* to the lock by means of the pins *l*. *y* represents an eye-hole in *b*.

As is shown, we obtain the object of our invention by inserting a piece of metal into the lock to be guarded, and attaching a second piece to the outside, the two being so formed that when inserted and attached they cannot be removed together, and then fastening the two together, thus preventing their removal and guarding the lock.

To use our invention on a lock having Towne's said patent attached to it, we attach *b* by slipping it on *z* until the eye-hole *t* in *b* comes opposite the key-hole *x*. We next insert *a* into the key-hole of the lock to be guarded. (In the drawings a Yale key is shown, as well as *a*, as the key of the lock to be guarded may often be used; but for manifold reasons we prefer to use a straight piece of metal, even when the regular key can be obtained.) The eye-hole *s* is so placed in *a* and the eye-hole *t* in the upright face of *b* that when *b* is attached and *a* inserted, as described, the eye-holes *s* and *t* come alongside of each other. We then fasten *a* and *b* together, which may be done, as shown in the drawings, by passing the shackle of a padlock through the eye-holes *s* and *t*, when it will be found that *a* and *b* cannot be withdrawn until released from each

other, they cannot be removed together, the regular key cannot be inserted into x , and consequently the lock will be guarded and our object attained.

5 To use our invention on the Perry and Isham locks, b is so shaped that it may be attached in the same way as the register of the lock is attached.

The large Perry and Isham locks have faces 10 similar to that shown at C. In these the register of the lock is attached by means of pins l and slots in the register similar to the slots m and n in b . In locks of this kind our invention is operated as follows: We attach b to 15 the face of the lock by means of the slots m and n and pins l in the same manner that the register of the lock would be fastened. The eye-hole y is so placed in b that when b is so attached it (y) comes directly over what we 20 call the "key-hole" x . We next insert a through the eye-hole y into the key-hole x . As before, the eye-hole s is so placed in a and the eye-hole t in the upright face of b that when b is attached and a is inserted, as described, the eye-holes s and t come alongside 25 of each other. We then fasten a and b together, as set forth, when it will be found that a and b cannot be withdrawn until released from each other, they cannot be removed together, the register cannot be attached to the 30 lock, and consequently the lock will be guarded and our object attained.

In the small Perry and Isham locks the face 35 is similar to that shown at C', the register being attached to the face of the lock by being slipped into the grooves shown at C' and D'. To operate our invention in these, we attach b by slipping it into the grooves, in the same manner as the register would be fastened, until 40 the eye-hole y is over what we call the "key-hole" x . On the face of the lock is usually a pin to stop the register in its proper place when being slipped on, and b is so made that when stopped in the grooves by said pin

the eye-hole y will be over x . We next insert 45 a through the eye-hole y into the key-hole x , and, again, the eye-hole s is so placed in a and the eye-hole t in the upright face of b that when b is attached and a is inserted, as described, the eye-holes s and t come alongside 50 of each other. We then fasten a and b together, as before, and with the same result, and our object is attained.

We do not wish to limit our improvement absolutely to the eye-holes s and t , as, instead 55 of eye-holes, rings may be fastened to a and b , through which the shackle of a padlock may be passed. We have simply described and shown the method of application that we prefer.

Having described our invention, what we desire to secure by Letters Patent is—

1. A lock-guard constructed of two parts, substantially as described—one part, as a , adapted to be inserted into the key-hole, the 65 other part, as b , adapted to be attached to the outside of the lock—the two parts being provided with means for attaching them together when in position, substantially as and for the purposes described.

2. The combination, in the hereinbefore-described lock-guard, of the straight piece of metal a , having an eye-hole, s , at its outer end, or the end not inserted in the lock, the piece of metal b , having an eye-hole, t , and means, 75 substantially as described, for attaching it to the outside of the lock, and the padlock c , all constructed substantially as described, so that when a is inserted in the lock and b attached to the outside the two may be fastened together by means of the padlock c and eye-holes s and t , substantially as and for the purposes described.

LYMAN RHOADES.
JOHN PHILIP SIPP.
